COMBINED MEMO PAPER ROLL AND PENCIL HOLDER

Merton L. Dodge, Seattle, Wash.

Application December 6, 1956, Serial No. 44,097

Term of patent 14 years

(Cl. D74—1)

Fig. 1.

Fig. 2.

I claim:

The ornamental design for a combined memo paper roll and pencil holder, as shown.
